UNITED STATES PATENT OFFICE

2,470,293

NOZZLE

Joseph B. D'Angelo, Tiffin, Ohio

Application February 14, 1946, Serial No. 647,498

1 Claim. (Cl. 128—239)

1

This invention relates to nozzles and more particularly to a syringe nozzle and the primary object thereof is to provide an improved device of this character which is so constructed as to supply a medicated fluid, usually water, over and into any affected parts of the body.

Another object of this invention is to provide a syringe nozzle with means whereby a medicant or other similar substance may be readily inserted into the head portion of the nozzle whereby when fluid is forced through the nozzle, it will mix with the aforementioned medicant to supply a medicated fluid to the affected parts of the body.

Another object of the invention is to so construct a syringe nozzle as will provide for quick and easy disconnection of the parts thereof whereupon a new supply of medicant can be placed within the head portion of the syringe nozzle and also to provide means whereby the various parts forming the syringe nozzle may be readily disconnected for loading, inspection or cleaning with facility.

A still further object of the invention is to so construct a syringe nozzle in such a manner that streams of fluid emitted from the nozzle will be directed both forwardly and rearwardly of the head portion of the syringe nozzle when it is used internally.

Other objects of the invention will become more apparent as the invention is more fully set forth in detail in the following specification and shown in the accompanying drawing, in which:

Figure 1 is a side elevation view of the syringe nozzle embodying my invention,

Figure 2 is a central vertical longitudinal section showing on an enlarged scale the syringe nozzle embodying my invention,

Figure 3 is a fragmentary view of the forward portion of the nozzle.

Figure 4 is a sectional view of the removable head portion of my improved syringe nozzle, and

Figures 5, 6 and 7 are transverse vertical sectional views taken on lines 5—5, 6—6 and 7—7, respectively, of Figure 2.

Referring now to the drawings wherein like reference characters denote corresponding parts throughout the several views, the syringe nozzle comprises a barrel 1 which is made of any suitable material such as hard rubber, plastic or other similar hard substance. However, if it is desired to have a certain amount of resiliency in this portion of the syringe nozzle, the barrel 1 could be constructed of some flexible material

2

such as soft rubber having sufficient stiffness to permit ready insertion of the nozzle within a body cavity.

A central bore 2 extends from the rear portion of the barrel member 1 to the forward portion thereof where it terminates in an enlarged mixing chamber generally located by numeral 3 in the drawing. Mixing chamber 3 is formed in the front end portion of the barrel 1 and is provided with a plurality of openings 4 slanted rearwardly thereof for a purpose to be more fully described hereinafter. As clearly shown in Figures 2 and 3 of the drawing, the mixing chamber 3 is formed within the slightly enlarged portion 6 of the nozzle which is internally threaded as shown at 7 and engages the reduced externally threaded portion 8 of the head portion 5 of the nozzle. The head portion 5 of the nozzle comprises a tubular member having a cylindrical bore 9 extending from the rear portion thereof to a point adjacent the front portion of the nozzle where it communicates with a series of openings 10 and 11 formed in the tip portion 12 of the nozzle.

Tip portion 12 comprises a tubular member formed integral with head portion 5. The head portion 5 of the nozzle can be molded of hard rubber or similar substance with openings 10 and 11 formed therein during the molding process or openings 10 and 11 can be formed therein as by drilling or boring these openings in the head portion of the nozzle 5. Openings 10 and 11 thus positioned in this portion of the head member 5 will direct streams of fluid forwardly of the nozzle when the device is in use.

Means are provided in the syringe nozzle for medicating the water or other fluid as it passes through the syringe nozzle and this means preferably comprises a soluble cake or cartridge 13 of medicinal material disposed within the cylindrical bore 9 of head portion 5 of the nozzle. Since the best results for medicating the fluid passing through the syringe nozzle are obtained when the soluble cake or cartridge is contained or disposed within the cylindrical bore 9 of the head member 5, the cake or cartridge should preferably be circular in form and of such a diameter as to permit easy insertion and withdrawal thereof from within the aforementioned bore 9.

The outer surface of head portion 5 is well-rounded and tapers slightly toward the front portion thereof which is reduced to form a small tip 12 in order to permit easy insertion of the

syringe within a body cavity when it is desired to use the device as a douche apparatus.

A nipple 14 is formed on the rear portion of the barrel 1 to which tubing 15 is connected in any well-known manner. Tubing 15 leads to a suitable fluid supply or fluid reservoir.

In use, a suitable medicant is placed within the cylindrical bore portion of the nozzle. The head portion 5 is then threaded into the enlarged portion 6 of the barrel 1 and the fluid supply tubing 15 is connected to the opposite end of the aforementioned barrel. When this has been accomplished, the tubing 15 is connected to a suitable source of fluid supply and the nozzle inserted into a body cavity if it is to be used as a douche apparatus and fluid is forced through the nozzle to treat the affected parts. Since the medicant 13 is located at a point materially in the rear of the discharge orifices or openings 10 and 11, the entire stream of fluid passing through the barrel 1 will be impregnated and permeated with and by the medicant to such an extent that the whole stream of fluid passing through the syringe nozzle is rendered medicinal. The medicant placed within the cylinder bore 9 will, to some extent, retard the flow of fluid through orifices or openings 10 and 11 formed in the front portion of head member 5 with the result that streams of medicated fluid will be directed rearwardly of the head portion of the nozzle through openings 4 provided in mixing chamber 3.

It is, of course, apparent that the medicant may be omitted entirely from the head portion of the syringe nozzle thereby permitting the free flow of water or other fluid through the openings 4, 10 and 11 when it is desired to supply an unmedicated water or other fluid to the affected parts. Likewise, it is, of course, obvious that instead of using a medicant in this portion of the nozzle, an anesthetic or antiseptic could likewise be placed in this portion of the syringe nozzle and the device used for various other purposes.

While a preferred specific embodiment of the invention is hereinbefore set forth, it is to be clearly understood that I am not to be limited to the exact construction illustrated and described, because various modifications of these details may be resorted to in putting the inven-

tion into practice within the purview of the appended claim.

I claim:

A syringe nozzle comprising a tubular barrel open at front and rear ends and having its rear end adapted for engagement with a fluid-supply tube, the front end portion of said barrel being of increased diameter and formed internally with a mixing chamber of greater diameter than the bore of said barrel and having an annular wall threaded from its front end, there being outlet openings extending radially from the rear end of the mixing chamber at a rearward incline through the annular wall thereof and spaced from each other circumferentially thereof, a head having an externally threaded neck at its rear end screwed into the mixing chamber of said barrel, said head being tapered towards its front end and having its front end portion reduced in diameter to form a tip, said head having a longitudinally extending pocket of less diameter than the mixing chamber forming a continuation of the mixing chamber at a rearward incline said head being formed with a centrally located outlet opening extending from the pocket through the tip longitudinally thereof and with other outlet openings surrounding the central outlet opening and extending from the pocket through side portions of the tip in spaced relation to each other circumferentially thereof, and an elongated medicant cartridge fitting loosely in the pocket of said head with its rear portion extending into the mixing chamber and its front end retarding free flow of fluid through the outlet openings of the head.

JOSEPH B. D'ANGELO.
